UNITED STATES PATENT OFFICE.

FREDERICK H. PERRY, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING UPON INSOLES.

Application filed February 9, 1921. Serial No. 443,571.

This invention relates to machines for operating upon insoles for boots and shoes and more particularly to a machine for trimming the margins of manufactured insoles such as are used in standardized welt shoes of the type fully disclosed in a co-pending application, Serial No. 476,659, filed June 11, 1921, in the name of George E. Warren.

Such standardized shoes are made by automatic machinery in which the shoe and the operating instrumentalities of the machine are moved relatively in a predetermined path, by mechanical means, to transfer the point of operation around the shoe. To obtain satisfactory results by the use of such machinery, it is important that all insoles of the same size and style be alike in all dimensions, particularly with regard to the relation of the sewing-rib to the edge of the insole. It has been proposed to produce standardized welt insoles of uniform dimensions for use in the manufacture of such standardized shoes by building up laminated structures of sheet insole material, each consisting of one or more body layers, and an outside layer having a grooved sewing-rib. The body layers for these insoles may be dinked to the exact size required for the finished insole, but the layer which is to form the sewing surface must be dinked to a larger size to provide material from which the sewing-rib is to be formed. It has been found difficult or impracticable so to cut the material for the layer which is to provide the sewing surface, that when the grooved sewing-rib has been formed, the area of the unribbed face of this layer will be equal to the surface area of the body layer. It is now proposed to preliminarily cut or die out all of the layers which are to be assembled in each insole to a size which will form a sole blank having a greater surface area than that of the insole ultimately to be produced, and subsequently to trim the sole to the exact size desired.

One of the objects of the present invention is to provide an efficient and reliable machine for performing such a trimming operation on welt insoles so as to produce insoles each having a sewing-rib which bears a predetermined relation to the edge of the insole.

In one aspect the invention resides in the provision of means for cutting shoe part blanks from pieces of material each pro-

vided with a positioning surface within the periphery of the proposed blank to be engaged by a positioning means within the cutting means operative to hold a piece of material against movement of translation in its own plane during a cutting operation.

Considered from another standpoint, the invention contemplates the provision, in a machine for trimming soles, of a die and a cooperating cutting-block, in combination with means for locating the margin of an untrimmed sole in a lateral direction relatively to the cutting edge of the die. In the illustrated embodiment of the invention, the margin of the sole is located relatively to the die by means of locating or gaging devices such as a jig pin carried by a work support upon which the soles are placed by the operator. The work support may also comprise a flat plate arranged to support the sole by engagement with its ribbed face, inside of the sewing-rib. In the illustrative construction, the sole-locating or gaging devices comprise a flat toe plate which is shaped to fit the space inside the sewing-rib at the toe of the insole, and a yielding jig pin which is adapted to enter one of a pair of jig-holes which, in the standardized insole construction, are punched through the sole before it is operated upon by the present machine and are used in locating the sole on the last bottom at the assembling operation. In order to provide a rapidly operating machine, it is preferred to employ two sets of dies and associated sole-supports and sole-locating devices, the dies being so arranged and actuated that when one die is cooperating with the cutting-block to trim the sole carried by the corresponding sole-support, the other die and its associated sole-support are retracted from the field of operation of the cutting-block to permit the trimmed sole to be removed from said support and a new sole placed thereon. To this end, each die and the sole-supporting and sole-locating devices associated therewith, are mounted upon an independent sliding carriage and these carriages are adapted to be actuated alternately toward and from the field of operations of the cutting-block.

Another object of the invention is to provide an insole trimming machine which may be readily adapted to produce trimmed insoles of different sizes and styles.

To this end, provision is made whereby dies of different sizes and styles may be interchangeably employed in the machine and different sizes and shapes of toe positioning plates may be interchangeably mounted upon the sole-supports. Provision is also made for quickly and accurately locating the die relatively to the associated sole-support and sole-locating devices and for securely clamping the die in its adjusted position so that when the sole has been placed in the proper position upon the sole-support, its margin will be located in the requisite relation to the cutting edge of the die.

The invention further consists in the features of construction and combinations of parts hereinafter described and particularly pointed out in the appended claims, the advantages of which will be apparent to those skilled in the art.

The various features of the invention will be best understood from the description of the preferred embodiment thereof illustrated in the accompanying drawings, in which:—

Figure 1 is a view, in front elevation, of the machine; Fig. 2 is a view, in side elevation, thereof, the rear portion of the machine being omitted (see Fig. 10); Fig. 3 is a sectional view, on an enlarged scale, taken substantially on the line 3—3 of Fig. 2; Fig. 4 is a top plan view, on a still further enlarged scale, showing one of the trimming dies, together with the corresponding sole-supporting and locating plate and the sliding carriage upon which said die and plate are mounted; Fig. 5 is a view in side elevation, of the parts shown in Fig. 4, together with a portion of the frame which supports the sliding carriages; Figs. 6 and 7 are sectional views taken on the lines 6—6 and 7—7, respectively, of Fig. 5, these figures being on a still further enlarged scale and illustrating particularly the mounting of one of the trimming dies and its associated sole-supporting and locating plate; Fig. 8 is a detail view showing a portion of the clutch control mechanism; Fig. 9 is a detail view showing another portion of the clutch control mechanism and a portion of the mechanism for rotating the cutting-block; and Fig. 10 is a fragmentary view, in side elevation, showing particularly the driving mechanism, this figure, with Fig. 2, forming the complete side elevation.

As shown in the drawings, the various operating parts of the machine are supported by a substantially rectangular frame or casting 20 (Figs. 1 and 2) having an overhanging front portion 22. The sole trimming instrumentalities comprise a pair of sole-shaped, right and left dies 24 and 26, and a cutting-block 28 which is adapted to cooperate with both dies. The dies 24 and 26 are mounted upon slideable carriages 30 and 32, respectively, which are reciprocable upon

horizontal guide ribs 33 (Fig. 1) that are formed on the upper part of the frame 20 and the carriages are adapted to be actuated to alternately advance the dies beneath the cutting-block into position to cooperate therewith. The cutting-block 28 is mounted upon a cross-head 34 which is reciprocated vertically above the frame 20 to cause the cutting-block to cooperate with the dies. The untrimmed soles are placed by the operator upon one or the other of a pair of horizontal sole-supports or plates 36 and 38 (Figs. 4 to 7) which are yieldingly supported by the carriages 30 and 32 and are severally located within the cutting edges of the dies 24 and 26. Each of these sole-supports 36 and 38 is normally positioned with its upper face elevated slightly above the adjacent cutting edge of the die so as to support a sole between the die and the cutting-block. Furthermore, the sole-locating devices on each sole-support are constructed and arranged to locate the sole with its margin overlapping the cutting edge of the die, and properly positioned relatively thereto, for the performance of the trimming operation. When the cutting-block cooperates with one of the dies to trim a sole, the corresponding sole-support is forced downwardly, inside of the die, and after the sole has been trimmed the support is returned to normal position and operates to strip the trimmed sole from the die.

The sliding carriages 30 and 32, carrying the dies and the sole-supporting plates, are of elongated rectangular form and are adapted to be reciprocated by means of cam-actuated mechanism including a pair of independent, continuously reciprocating actuator slides 40 and 42 (Fig. 2). The slides 40 and 42 are normally disengaged from their respective carriages 30 and 32, and are adapted to be connected therewith, under the control of the operator, to cause said carriages to be advanced alternately beneath the cutting-block 28 into position for the trimming operation. The cross-head 34 is reciprocated to cause the cutting-block to cooperate with the dies by means of cam-actuated, clutch-controlled mechanism including a pair of eccentrics 44 (Figs. 1 and 2). Rigidly secured to the upper face of each carriage at the forward end thereof, by means of screws 45 (Figs. 4 and 5) is a supporting frame or carrier 46 upon which the die and the associated sole-supporting and locating devices are mounted.

Each die, as shown in Figs. 4 to 7, inclusive, consists of the usual endless steel band, one edge of which is beveled to form a cutting edge. The pair of dies are arranged with their cutting edges uppermost to cooperate with the cutting-block, and with their lower edges resting upon the horizontal upper faces of the die-carriers 46. The

5 dies are located upon the die-carriers relatively to the associated sole-supporting and locating plates and are clamped to the die-carriers in the desired location by means of devices, the construction and operation of which will be hereinafter described in detail.

10 The sole-supporting plates 36 and 38, as best shown in Figs. 4 to 7, inclusive, are adapted to support the soles just above the cutting edges of the dies and the sole-locating or positioning devices carried by the sole-supports are adapted to locate the soles both longitudinally and transversely relatively to the dies, so as to properly position them for the trimming operation. When thus located, the sole margins will overlap the cutting edges of the respective dies, as shown in Fig. 5, in which a standardized welt insole is indicated at S.

15 20 The sole-supporting plates 36 and 38 are shaped to cooperate with the right and left dies 24 and 26, but otherwise they are identical in construction and mode of operation. Accordingly, it will be necessary to describe 25 only one of these plates in detail. Each sole-supporting plate 36 is supported in a horizontal position, within the open end of the die 24, by means of a pair of vertical posts 48 (Fig. 5) to the upper ends of which 30 the plate is removably secured. As shown, the reduced upper ends of the posts 48 extend through openings in the sole-locating and supporting plate 36, bosses on the under face of the plate resting upon collars 50 on the posts. The plate 36 is removably secured in position on the supporting posts by means of screws 52 threaded into the posts 48, the heads of said screws overlapping the upper ends of the posts and fitting 35 within countersunk recesses in the upper face of the plate. The supporting posts 48 extend freely through guideways 54 which depend from the under side of the top wall of the die-carrier 46. The lower extremities 40 of the posts 48 are rigidly connected by means of a cross-bar 56.

45 Normally, the supporting plate 36 is held yieldingly in the position shown in Fig. 5, with its upper edge projecting somewhat above the horizontal plane of the cutting edge of the die, and is adapted to yield downwardly under pressure of the cutting-block when the latter cooperates with the die. To this end, the weight of the plate 36 50 is supported by a spring-pressed plunger 58 which projects upwardly from the die-carrier 46. The plunger fits within a depending guideway 60, like the guideways 54, and rests upon a coiled spring 62 which is confined beneath the plunger by means of a screw 64 that closes the lower end of the guideway and may be turned to vary the tension of the spring. The upper position 55 of the plunger 58, and consequently the normal elevation of the sole-supporting plate

with relation to the cutting edge of the die, is determined by means of a head 66 on the lower end of the plunger 58 which engages a shoulder at the upper end of the guideway 60 to limit the upward movement 70 of the plunger under the influence of the spring 62. By means of the cross-bar 56, which connects the two supporting posts 48, the sole-supporting plate 36 is caused to retain its horizontal position as it is 75 depressed by the cutting-block, thus eliminating any possibility of the posts 48 binding in their guideways.

80 In order that the insole may be located in a definite position relatively to the die when placed by the operator upon the sole-support, sole-locating or positioning devices are provided, including a toe and forepart gage 68 which is adapted to engage the sewing-rib at the toe of the insole. The toe and forepart gage 68 consists of a thin flat plate which is adapted to enter the space inside the sewing-rib at the toe of the insole and is removably secured to the upper face of the sole-support by means of screws 70. The toe gage or plate 68 is so shaped that its edge fits accurately the contour of the inside of the sewing-rib at the toe of the insole. To firmly hold the sole against possible slipping when placed, ribbed face down, upon the sole-support, one or more pointed prongs 72 project forwardly from the tip of the toe plate and are adapted to penetrate the material of the sewing-rib adjacent the base of its inner side at the point of the toe. As shown in Figs. 4 and 5, the prongs 72 are conveniently formed upon a small plate 74 which is secured to the upper face of the toe plate 68.

90 95 The toe end of the insole is located before the heel end thereof. The sole is placed, ribbed face down, upon the sole-support, in such a way that the toe plate will lie within the space inside the sewing-rib. The operator then urges the sole rearwardly to insure 100 that the prongs 72 will penetrate the sewing-rib to prevent edgewise displacement of the toe end of the sole. When the insole has been positioned so that the inner face of 105 its sewing-rib is in contact with the edge of the toe plate 68, the toe end of the sole will be located substantially in the requisite relation to the cutting edge of the die.

110 115 To locate the heel end of the insole and to insure that the entire sole will be located with absolute accuracy for the trimming operation, the sole locating devices also include a jig pin 76 which is mounted at the heel end of the sole-support and is adapted to enter the rearmost of a pair of jig-holes 120 which are punched through the heel ends of standardized welt insoles of the type above referred to, before they are ready to be trimmed. These jig-holes, which are indicated at 78 in Fig. 5, are provided for the 125 130

purpose of receiving jig or positioning pins on the last or on other work supports which are employed in the manufacture of shoes in accordance, for example, with the method disclosed in the Warren application above identified.

The jig pin 76 which may be of any well-known construction, is adapted to yield downwardly to permit the sole to lie flat upon the sole-support while being located thereon, and the pin is spring-pressed upwardly to cause it to snap into the rearmost jig-hole when said hole is brought into registry with the rounded upper end of the pin. The pin is located on the longitudinal center line of the heel portion of the sole-support at a predetermined distance from the tip of the toe plate 68, the position of the pin being such that when a sole has been placed upon the sole-support and carefully located with the inner side of the sewing-rib in contact with the curved edge of the toe plate, throughout the length of said edge, the rearmost jig-hole will be located to receive the pin. As will be hereinafter explained, the die is subsequently located, with respect to the toe plate 68 and the pin 76 in such a manner that when the sole has been positioned on the sole-support by means of the toe plate and the pin, the sole margin will be trimmed in the requisite relation to the sewing-rib.

In locating a sole, if the jig pin 76 has not already entered the rear jig-hole in the sole, when the sewing-rib is engaged by the prongs 72 on the toe plate 68, the operator shifts the sole slightly in a lateral edgewise direction until the hole is brought into registry with the pin, whereupon the pin snaps into the hole. The sole is then properly located, both longitudinally and transversely with respect to the die. The employment, in each sole-supporting plate, of the spring-pressed positioning pin 76 insures absolute accuracy in the positioning of the various soles, inasmuch as the pin cannot snap into the hole in the sole until the sole is located in exactly the proper position with respect to the die. When the jig pin does enter the hole in the sole, the operator will know that the sole has been properly located.

To enable the machine to operate upon various sizes of soles, it is contemplated that a plurality of dies of different sizes will be provided which are adapted to be interchangeably received in the machine. When the dies employed in the machine are replaced by a new pair of dies of a different size, it is necessary to make a corresponding change in the toe plates 68 in order that the latter shall properly perform their functions of locating the sole margins for the trimming operation. By removing the screws 70, the toe plate 68 may be readily

removed to permit the substitution of another toe plate of a different size therefor.

While in the construction illustrated and described, a removable toe plate has been employed for engaging the sewing-rib to locate the toe end of the insole, similar results may be obtained without the use of such means by shaping the sole supporting plates 36 and 38 so that they will exactly fit the space inside the sewing-rib. In this way the edge of each sole-supporting plate will engage the inside of the sewing-rib throughout the entire length of the latter. When such construction is employed, it is contemplated that a plurality of sole-supporting plates of different sizes and styles will be provided to correspond to the various sizes and styles of dies, these plates being adapted to be interchangeably mounted upon the die carrier. When a die of a different size is employed in the machine, the sole-supporting plate may be readily removed by withdrawing the screws 52 to permit the substitution of another sole-supporting plate corresponding in size and style with the new die.

In order that the sole-supporting and locating devices may properly locate the margins of the soles relatively to the cutting edges of the corresponding dies, it is necessary that the dies shall be preliminarily located, with absolute accuracy, relatively to the corresponding sole-supporting and locating devices. To this end, the following means is provided for determining the requisite transverse and longitudinal relation of each die to its die-carrier, and consequently to the associated sole-supporting plate.

The means for determining the transverse relation of the die to its carrier comprises two locating tongues or keys 84 and 86, (Figs. 4 and 5) which are rigidly secured to the top face of the die-carrier 46 at opposite ends thereof, and which extend longitudinally of said carrier in alignment with each other. These tongues or keys 84 and 86 are adapted to enter grooves or keyways 88 and 90, respectively, which are disposed in alignment with each other and which extend transversely across the lower edge of the die at the toe and heel ends thereof. The key 84, for positioning the toe end of the die is of sufficient length to insure its engagement in the keyway 88 when the die has been located longitudinally upon the die-carrier, irrespective of the length of the die employed.

The means for longitudinally positioning the die on the die-carrier comprises a lug 92 which rises from one end of the key 86 and is adapted to engage the inner face of the die, and a positioning bolt 94 which is threaded through an ear 96 rising from the opposite end of the key 86, the inner end of said bolt being adapted to engage the outer

face of the die at a point directly opposite that engaged by the lug 92. The positioning bolt 94 may be adjusted by turning its knurled head to provide space for the reception of the heel end of the die between the bolt 94 and the lug 92. A lock-nut 98 is provided for securing the positioning bolt 94 in adjusted position. The lower edge of the key 86 is received in a groove in the upper wall of the die-carrier and is located and held in the groove by a dowel pin 100 which enters a hole in the die-carrier.

The above described construction for locating the die on the die-carrier insures that the die will be readily and accurately located, both transversely and longitudinally, with respect to the sole-locating devices on the sole-support. By means of the lug 92 and the positioning bolt 94 on the key 86, it will be seen that all dies will be positioned longitudinally of the die-carrier with their rear extremities located at the same distance from the spring pin 76. It should be pointed out that the rearmost positioning pins on all lasts within a certain range of sizes will be located at the same distance from the rear extremities of the last bottoms, irrespective of the size or style of the last. Also the rearmost jig-holes in all insoles within a corresponding range of sizes are so located that the distances between these holes and the rear extremities of the insoles, after the latter have been trimmed, will be the same. By reason of these facts, when a die of a size within the above mentioned range is placed upon the die-carrier with its rear end located between the lug 92 and the bolt 94, the toe end of the die will be properly located longitudinally with respect to the toe plate 68. This construction permits dies of the different sizes within the range above mentioned, to be interchangeably received in the machine without the necessity of making any preliminary adjustment of the die locating devices. In order to provide for properly positioning other dies, the sizes of which are beyond the range above referred to, the present invention contemplates the provision of a plurality of keys 86 which are adapted to be interchangeably mounted on the die-carrier and which are adapted to be located thereon with their lugs 92 at different distances from the spring pin 76. The lugs 92 may be located in the required positions by varying the location of the dowel pins upon the several keys.

To securely clamp the dies in their adjusted positions upon their respective die-carriers, two sets of clamping devices are employed, one set being arranged to engage the heel portion of the die and the other set to engage the toe portion thereof. These die-clamping devices are mounted on the die-carrier 46, and comprise two pairs of horizontal clamping studs which are movable axially to bring them into engagement with corresponding holes in the dies and are adapted to be depressed laterally to clamp the dies against the die-holders. One pair of clamping studs, as best shown in Fig. 6, 70 are indicated at 102 and 104, and are disposed in axial alignment just above the upper face of the die-carrier. The clamping studs 102 and 104 are movable axially toward and from each other to cause them to severally enter or withdraw from a pair of corresponding clamping holes 106 and 108 which extend through the wall of the die adjacent the heel end thereof. The other pair of clamping studs, as best shown in Fig. 7, are 80 indicated at 110 and 112, and are adapted to severally engage within a pair of clamping holes 114 and 116 extending through the walls of the die adjacent the toe end thereof. The clamping studs 110 and 112 are adapted 85 to move in an axial direction, or substantially so, as they are projected into, or retracted from, their respective clamping holes in the die. The several clamping holes are bored perpendicularly through the side walls 90 of the die. The holes 106 and 108, adjacent the heel end of the die, are arranged with their axes coincident and normal to the longitudinal center line of the die. The coincident axes of the holes 106 and 108 are spaced 95 the same distance from the rear extremity of the heel portion of the die in the various dies which are to be interchangeably employed in the machine, irrespective of the sizes of these dies. The holes 114 and 116 100 adjacent the toe end of the die, are so arranged that they may be entered by their respective clamping studs 110 and 112 when the die is located in position to receive the clamping studs 102 and 104 for the heel end 105 of the die.

To permit the clamping studs 102 and 104 to be moved transversely of the die-carrier for the purpose of projecting them into, or withdrawing them from, the corresponding 110 clamping holes in the die, after the die has been located upon the die-carrier as above described, said studs are carried at the upper ends of a pair of clamping arms 118 and 120, respectively, (Figs. 5 and 6). The 115 clamping arms 118 and 120 are mounted to slide laterally upon a rod 122, the ends of which are secured in the arms of a yoke-shaped support 124. At one end of the support 124 the arms whereof are pivoted upon 120 studs 126 projecting inwardly from the side walls of the die-carrier. At its opposite ends, the pivoted support 124 is acted upon by a spring 128 (Fig. 5) which presses the support 124 upwardly against the lower end 125 of an adjusting screw 130, (Figs. 4 and 5) which is threaded through the upper portion of the die-carrier. In this way, the clamping studs 102 and 104 are positioned 130 the requisite distance above the top of the

die-carrier to permit them to freely enter the clamping holes in the die.

When the clamping studs are disengaged from the die, they are so located transversely of the die-carrier as to lie within the walls of the die when the latter is placed upon the die-carrier and located thereon by means of the keys 84 and 86. In order to introduce the clamping studs 102 and 104 into the corresponding clamping holes in the die, the clamping arms 118 and 120, carrying said studs, are adapted to be shifted independently upon the rod 122. The means for shifting the arm 118 comprises a thumb-screw 132 which is screw-threaded through one side wall of the die-carrier and is reduced at its inner end to extend freely through a vertical slot 134 in said arm. A pair of fixed collars 136, (Fig. 6) upon the reduced inner extremity of the thumb-screw 132 engage opposite sides of the clamp arm 118 causing said arm to slide laterally upon the rod 122, in one direction or the other, as the thumb-screw 132 is turned by means of its knurled head. The clamping arm 120 is slidably adjustable on the rod 122 in a similar manner, by means of an adjusting rod 138 which is screw-threaded at one end through the side wall of the die-carrier beneath the thumb-screw 132, while the opposite end thereof extends through a bearing in the opposite side wall of the die-carrier. Between the side walls of the die-carrier, the unthreaded portion of the adjusting rod 138 passes through a slot 140 in the end of an extension 141 depending from the clamping arm 120. A pair of fixed collars 142, which are secured to the unthreaded portion of the adjusting rod 138, engage opposite sides of the extension 141, causing the clamping arm 120 to slide on the shaft 122 when the adjusting rod 138 is turned by means of a knurled head thereon.

After the clamping studs 102 and 104 have been projected into the corresponding clamping holes in the die, the screw 130 is turned, depressing the free end of the pivoted support 124 sufficiently to cause said clamping studs to bind against the bottoms of the clamping holes, and thus firmly clamp the heel end of the die against the upper face of the die-carrier. The slots 134 and 140 in the arms 118 and 120 are of sufficient length to permit the requisite amount of relative movement between the clamping arm 124 and the adjusting studs 132 and 138 when the clamping arm is depressed.

The clamping studs 110 and 112 for the toe end of the die project horizontally from the upper ends of the two vertical posts 144 and 146 which have provision for lateral movement toward and from each other in segmental slots 148 extending through one end of a substantially horizontal supporting plate 150, the opposite end of which is pivoted between a pair of horizontal studs 152

extending inwardly from the side walls of the die-carrier. As shown in Fig. 5, the lower extremities of the posts 144 and 146 are reduced in diameter to extend through the slots 148 in the supporting plate 150, and suitable collars 154 are provided above and below said supporting plate, the upper collar engaging a shoulder formed at the junction of the reduced lower extremity of the post with the upper portion thereof, and the lower collar 154 resting upon a nut 156 on a screw-threaded portion of the post. The clamping posts 144 and 146 are mounted with provision for turning movement in the slots 148 to permit the studs 102 and 104 to adjust themselves to the holes in the die, as will be hereinafter explained. In order that the posts 144 and 146 may be at all times free to turn and also to slide laterally in the slots 148, a lock-nut 158 is provided which may be tightened against the nut 156 so as to prevent the latter from binding the post in adjusted position on the supporting plate 150. When the clamping studs 102 and 104 are retracted from the die, the weight of the supporting plate 150 is sustained by suitable springs 160 which force the plate upwardly against an adjusting screw 162, the latter extending vertically through the top wall of the die-carrier and being threaded therein.

Inasmuch as the opposite side walls of the die adjacent the toe end thereof are disposed at more or less of an angle to the center line of the die, as shown in Fig. 4, the clamping holes 114 and 116 which extend perpendicularly therethrough, will not be in axial alignment as in the case of the clamping holes 106 and 108 at the heel end of the die. Consequently, in order to insure the introduction of the clamping studs 110 and 112 into the clamping holes 114 and 116, the studs are mounted to move toward and from the side walls of the die in arcuate paths about the centers of curvature so located that the studs will be caused to enter the holes in a substantially axial direction. To this end, the segmental slots 148 are curved, as shown in Fig. 4, and the clamping posts 144 and 146 are adapted to be shifted therein by means of a pair of levers 164 and 166, respectively, which are fulcrumed on studs 168 depending from the top wall of the die-carrier, and are provided at one end with bearings in which the clamping posts are free to turn and slide. The axes of the fulcrum studs 168 are coincident with the centers of curvature of the segmental slots 148. The difference in curvature in the opposite side walls at the toe end of the die may be such that the section of the wall adjacent one of the clamping studs will not be disposed in perpendicular relation to the path of movement of the stud. An example of such a condition is illustrated in Figure 4, in

which the section of the wall adjacent the clamping hole 116 is not perpendicularly disposed with relation to the path of movement of the clamping stud 112 as said stud 5 enters the hole. In such a case, the post, upon which the clamping stud is mounted, is permitted to turn in its bearing upon the corresponding actuating lever after the stud has entered the hole in the die so that the 10 stud will adjust itself to the hole.

The supporting posts 144 and 146 are adjusted independently toward or from each other to project the clamping studs carried thereby into the clamping holes in the die 15 or to retract the studs from said holes. To this end, the lever 164, at one end of which the post 144 is mounted, is connected at its opposite end by means of a link 170 (Fig. 7) with a slide 172 which is mounted in the 20 die-carrier to slide transversely with respect thereto. The slide 172 is actuated by means of an adjusting stud 173 which is screw-threaded into a longitudinal socket in the slide 172 and extends through and is adapted to turn freely in a slotted plate 174, that is rigidly secured to the outside of the die-carrier 46. The adjusting stud 173 is provided with two fixed collars 175 which engage opposite sides of the plate 174, and with a knurled head at its outer end. With this construction, when the adjusting stud 173 is turned by means of its knurled head, the slide 172 will be shifted in one direction or the other for the purpose of adjusting 30 the post 144. The lever 166, upon one end of which the clamping post 146 is mounted, is connected at its opposite end by means of a link 176 with a slide 178 which is mounted above the slide 172 in suitable 35 bearings in the die-carrier. The slide 178 is actuated by means of an adjusting stud 180, corresponding to the stud 173, the stud 180 having a screw-threaded shank entering a socket in the slide 178, and a 40 knurled head mounted like the head of the adjusting stud 173. The stud 180 may be turned by means of its knurled head to actuate the slide for the purpose of adjusting 45 the clamping post 146.

50 After the clamping studs 110 and 112 have entered the corresponding clamping holes in the die, the adjusting screw 162 is turned to depress the free end of the supporting plate 150. The depression of the 55 supporting plate 150 causes the clamping studs 110 and 112 to bind against the bottoms of the clamping holes so that the toe end of the die is firmly clamped against the upper face of the die-carrier.

60 The carriages 30 and 32, upon which the trimming dies and the sole-supporting and locating plates are mounted, are actuated to advance the dies and the soles beneath the cutting-block by means of the actuator slides 40 and 42 (Fig. 2). The actuator slides are

70 mounted for horizontal sliding movement in guideways 182 and 184, (Figs. 1 and 3) that are formed in the upper part of the machine frame. As shown in Fig. 2, each actuator slide is provided with a hooked forward extremity 186 (Fig. 2) by means of which the slide is adapted to be operatively connected with the carriage to move the carriage in a rearward direction so as to advance the die beneath the cutting-block. Each actuator 75 slide is further provided with an up-standing lug 188 which is adapted to engage a shoulder 190 on the carriage to move the carriage in a forward direction so as to return the die to its sole receiving position. The actuator slides are continuously reciprocated throughout the operation of the machine by means of cam-actuated mechanism.

The mechanism for reciprocating the actuator slides 40 and 42 comprises a pair 80 of cam levers 192 and 194 (Figs. 2 and 3) which are pivoted at their lower ends upon a common fulcrum rod 196, transversely extending across the lower part of the frame 20, the levers being severally connected with the respective actuator slides by means of links 198. Each lever 192 and 194 carries a cam roll 200 and these rolls are severally received in cam paths formed in a pair of cam disks 202 that are secured to a cam 85 shaft 204 journaled in the opposite walls of the frame 20. The cam disks 202 are designed to reciprocate the carriages once for each revolution of the cam shaft and they are so adjusted on the shaft relatively 90 to one another, as to cause the carriages to move alternately in rearward and forward directions. The cam shaft 204 is connected, by means of intermeshing worm gearing 206, (Fig. 10) with a counter shaft 208, 95 which is driven through intermeshing worm gearing 210 from a main shaft 212 which, as shown, may be the armature shaft of a motor or the shaft may be driven from any 100 suitable source of power.

To facilitate the placing of the soles upon the sole-supporting and locating plates 36 and 38, the carriages 30 and 32, which carry these plates, are severally adapted to be disconnected from their actuator slides after 115 each reciprocation of the carriage and are normally maintained stationary with the sole-supporting plates retracted from beneath the cutting-block, in which position they receive the soles. To this end, the carriages are 120 severally connected with their actuator slides by means of coupling members 216 (dotted lines Fig. 5), one of which is mounted on each carriage and is arranged to engage the forward extremity of the respective actuator slide to effect the rearward movement of the carriage and to be automatically disengaged from the slide upon the forward or return movement of the latter. Locking bolts or latches 218 are provided to insure 125 130

that the carriages will be maintained stationary in their forward or normal positions. While one of the carriages is locked in its forward position, a sole is placed on the supporting plate carried thereby and is located by the plate relatively to the adjacent die.

When a sole has been placed upon one of the sole-supporting and locating plates and located thereby relatively to the die associated therewith, said supporting plate and die, together with the sole, are ready to be moved rearwardly into position for the sole to be trimmed by the pressure of the cutting-block on the die. For the purpose of initiating the rearward movement of the sole and die, provision is made whereby, at the will of the operator, the carriage carrying the die, above which the sole is located, may be unlocked and operatively connected with its respective actuator slide. To this end, each carriage is provided with mechanism including a trip-rod 220 which is adapted to be depressed by the operator to withdraw the locking bolt 218 from engagement with the carriage. At the same time the coupling member 216 which is normally latched out of position for engagement by its respective actuator slide, is unlatched by the depression of the trip-rod 220 and permitted to move into the path of movement of the hook 186 of said actuator slide.

When one of the carriages is thus connected with its actuator slide, it is moved rearwardly to advance its die and sole-supporting plate into position for the performance of the trimming operation. The carriage is momentarily arrested in this position while the cutting-block rapidly descends to trim the sole. The block immediately thereafter returns to its normal elevated position, the carriage is then free to be moved forwardly by its actuator slide, the slide at this time engaging the carriage directly through the medium of the lug 188 thereon, which engages the shoulder 190 on the carriage (see Fig. 2). During the forward or return movement of the carriage, the coupling member 216 is disengaged from the actuator slide and the carriage is finally brought to rest and locked by the bolt 218 in its extreme forward position.

The locking bolt or latch 218 and the coupling member 216, together with the trip-rod 220 and associated mechanisms for controlling the operation of each of the die-carriages are identical in construction and mode of operation and consequently it will be necessary to describe only one set of said parts and mechanisms in detail. As shown in Fig. 5, the locking bolt 218, which locks the carriage 30 in its forward position, is supported and guided for vertical sliding movement in bearings on the overhanging portion 22 of the frame 20. At its upper end the locking bolt

218 is provided with a shoulder 224 adapted to be engaged by a latch 226, which is pivoted at 228 upon the carriage 30 and is yieldingly held by means of a spring pressed plunger 230 against a stop pin 232, which locates the latch in position to engage the locking bolt when the carriage is in its forward position. The locking bolt 218 is urged downwardly by means of a spring 233, one end of which is secured to the frame portion 22 and the opposite end thereof to an arm 234 depending from a rocker member 236 journaled in the frame and having a horizontal arm 238 extending forwardly and entering a recess 240 in the side of the locking bolt. Normally the locking bolt is maintained in its raised or operative position against the tension of the spring 233 to cooperate with the latch 226 by means of a latch 242 which is pivoted at 244 upon the machine frame and is adapted to be held by means of a spring 246 in engagement with a second horizontal arm 248 upon the rocker member 236. The latch 242 is adapted to be tripped to release the locking bolt 218 by means of a vertical plunger 250 which is mounted to slide in a suitable bearing in the frame. The plunger 250 is provided with an enlarged head 252 which is adapted to be engaged by the lower end of the trip-rod 220, the latter being so arranged upon the carriage 30 that it will be located in position to operatively engage the head of the plunger 250 when the carriage is in its forward position.

The trip-rod 220 associated with the carriage 30 is mounted for vertical sliding movement in bearings 256 upon the side of the die-carrier 46. The trip-rod is urged upwardly by means of a coiled spring 258, which surrounds the rod between the lower bearing 256 and a collar 260 that is secured to the rod. Upward movement of the trip-rod 220 is limited by means of a stop-collar 262 upon the rod which is adapted to engage the under face of the lower bearing 256; this collar and the lower end of the rod lying within a housing 263 on the side of the carriage 30. At the top of the trip-rod is a thumb button 264, by means of which the rod may be depressed against the force of the spring 258. When the carriage 30 is in its forward position, depression of the trip-rod 220 will, by depressing the plunger 250, swing the latch 242 in a direction to disengage it from the arm 248 on the rocker member 236. This permits the spring 233 to swing the arm 238 downward to withdraw the locking bolt 218 from engagement with the latch 226 on the carriage 30, thus releasing the carriage.

In addition to unlocking the carriage 30, the depression of the trip-rod 220 also operates to set the coupling member 216 in position to be engaged by the actuator slide 130

42 to effect the advance of the sole to a position beneath the cutting-block when said slide next travels rearward. The coupling member 216 is pivoted at 266 to the under 5 side of the carriage 30 and is provided with a hooked end 268 which is adapted to cooperatively engage the hooked extremity of the actuator slide 42. A spring 270, one end of which is connected to the carriage 30 and the opposite end to a vertical arm 272 of the 10 coupling member, tends to swing the hooked end of the latter into engagement with the actuator slide. Normally, however, the coupling member is held out of engagement 15 with the actuator slide by means of a latch 274 which is pivoted at 276 to the carriage 30.

In order that the coupling member 216 may be actuated by means of the trip-rod 220 to effect the connection of the carriage 30 with the actuator slide 42, the following 20 connections are provided between the latch 274 and the trip-rod whereby the latch may be disengaged from the arm 272 of the coupling member. The latch 274 is provided with a downwardly extending lug 278, by means of which it is operatively connected with the rear end of a slide bar 280 which is supported and guided in bearings 282 upon 25 the under side of the carriage 30. The forward end of the slide bar 280 is adapted to be engaged by an arm 284 depending from a rockshaft 286 which is journaled in the carriage 30, and has projecting therefrom, a horizontal arm 288, the end of which lies below the lower face of the stop collar 262 on the trip-rod. A spring 289, which surrounds the slide-bar 280, between the rearmost bearing 282 and a collar 290 fast 30 on the slide-bar, normally holds the slide-bar in the position indicated in Fig. 5, with the latch 274 holding the coupling member 35 in inoperative position and with the arm 288 of the rock-shaft 286 held in contact with the collar 262 on the trip-rod. With this construction, depression of the trip-rod 40 will move the slide bar in a direction to lift the latch 274, releasing the coupling member 216 and permitting the spring 270 to swing the latter downwardly to bring its hooked end 268 into the path of the actuator slide 42 so that it will be engaged by the hooked extremity 186 of the slide when the latter reaches its forward position. The 45 locking bolt 218 being at this time withdrawn from engagement with the latch 226 on the carriage 30, the carriage will travel with the actuator slide, as the latter moves rearwardly, and the sole and die supported 50 upon the carriage are thus brought beneath the cutting-block.

As the carriage 30 approaches the limit 55 of its rearward movement, the locking bolt 218 is automatically reset so that it will again be engaged by the latch 226 when the

carriage has been returned to its normal forward position. For the purpose of resetting the locking bolt 218, the rock-shaft 236 is provided with an upwardly extending arm 291, (Fig. 5) which is connected by 70 means of a link 292 with a locking bolt controlling dog 293 that is pivoted upon a stud 294 projecting from the frame 20, the link 292 having a pin-and-slot connection with the arm 291, as indicated at 295. A spring 75 296, which is coiled around the pivot stud 294, normally holds the dog 293 in the position in which it is shown in Fig. 5, with a toe 297 which is formed at the upper end of the dog located in the path of a depending 80 lug 298 that is formed upon the extreme forward end of the carriage. This position of the dog 293 is determined by the engagement of a stop-screw, carried by a tail 299 depending from the dog, with a suitable 85 projection on the frame. Just before the carriage 30 reaches its rearmost position, the lug 298 on the carriage engages the toe 297 on the dog 293, swinging the dog 293 against tension of the spring 296, so as to 90 rock the shaft 236 and raise the arm 238, which in turn raises the locking bolt 218. The upward movement of the arm 238 carries the arm 248 with it to a position where it is engaged by the latch 242, at which time 95 the parts are all reset.

When the carriage 30 has reached its rearmost position so that the sole and the die have been properly located for the performance of the sole-trimming operation, the carriage is caused to remain stationary, momentarily, by virtue of a dwell in its actuating cam 202, while the cutting-block descends to cooperate with the die to trim the sole. Immediately after the sole has been trimmed, 105 the cutting-block is raised to normal position to permit the return of the carriage.

The cutting-block 28, as shown in Figs. 1 and 2, is composed of a plurality of strips of wood, or other suitable material, which are assembled in side-by-side relation, the whole being of cylindrical shape and arranged with one of its end faces directed downwardly and disposed in a horizontal plane to provide a cutting face to cooperate 110 with the trimming dies. The component parts of the cutting-block are bound together by an annular band 300. The cutting-block is removably secured to a holder 304 by means of clamping bolts 302, the heads of which overlap the lower edge of the band 300. Projecting upwardly from the cutting-block holder is a vertical cylindrical stem 306, which is adapted to turn in suitable bearings in the central portion of 115 the cross-head 34. The stem 306 is supported in the bearings 308 by a cap plate 310, which is secured by means of bolts 312 to the upper end of the stem 306.

The opposite ends of the cross-head 34 rest 120

upon a pair of hollow vertical posts 314 which extend through and are adapted to slide in bearings 316 projecting from opposite sides of the frame 20. To support the posts 314 in their bearings 316, and permit vertical adjustment of the cross-head to compensate for wear on the cutting-block, a pair of vertical rods 318 severally extend through the two hollow supporting posts 314, and are co-axially disposed therein with relation to the posts. The lower end of each rod 318 extends through a bearing 320 that is formed within the lower end of the respective supporting post 314. At its upper end, each rod 318 extends through a bearing sleeve 322, which is externally screw-threaded to be received in a screw-threaded socket in the cross-head. The weight of the cross-head is received by a pair of annular flanges 324, severally formed upon the rods 318, which engage the lower ends of the bearing sleeves 322. The upper extremity of each rod 318 is screw-threaded to receive a nut 326 and lock-nut 328, the former engaging the upper end of the bearing sleeve 322 to maintain the rod 318 in its assembled relation with the bearing sleeve. At their lower ends the rods 318 are severally connected by means of pivot studs 330 with a pair of eccentric straps 332, the latter encircling the eccentrics 44 by means of which the cross-head is supported and actuated, these eccentrics being keyed to the opposite ends of a shaft 334 that is journaled in bearings in the frame 20, and driven as will be hereinafter explained.

To compensate for wear upon the cutting-block, provision is made for simultaneously turning the screw-threaded bearing sleeves 322 in their sockets in the cross-head. To this end, each bearing sleeve 322 is extended upwardly beyond the nuts 326 and 328, as indicated at 340, and splined upon each extension 340 is a worm-wheel 342, which is confined within a housing 344 on the cross-head. Intermeshing with each worm-wheel 342 is a worm gear 346, the worm gears being secured upon the horizontal shaft 348, which is provided at one end with a hand wheel 350 by means of which the shaft may be turned to effect the simultaneous rotation of the two bearing sleeves 322. It will be seen that the turning of the bearing sleeves 322 will raise or lower the supporting posts 314 relatively to the rods 318, thus adjusting the cutting-block vertically without varying the length of stroke of the cross-head. The extensions 340 of the rods 318 are laterally cut away at opposite sides of the nuts 326 and 328 to afford access to the nuts in assembling.

To effect a reciprocation of the cross-head 34, the eccentric shaft 334 is adapted to be driven from the power shaft 212. To this end, the shafts 334 and 212 are con-

nected by means of a belt 352 (Fig. 10) which passes over a pulley 354, fast on the power shaft 212, and over a pulley 356, loosely mounted upon the eccentric shaft 334, which is adapted to be connected with the latter shaft by means of a clutch 358. The clutch 358 is periodically operated to cause the eccentric shaft to make one revolution and then automatically to be brought to rest. The construction and mode of operation of the clutch 358 is substantially the same as that of the clutch illustrated, described and claimed in Letters Patent of the United States, No. 1,011,903, granted December 19, 1911, to Arthur Bates, to which reference may be had for a full and clear understanding of the same. As set forth in said patent, the operation of the clutch is controlled by a clutch lever such as that indicated at 360 in Fig. 2. When the clutch lever 360 is in its normal position, in which it appears in said figures, the clutch is inoperative and the eccentric shaft is maintained stationary. By tripping the clutch lever 360, the clutch may be operated to connect the eccentric shaft with the pulley 356, and thereafter to disconnect the shaft therefrom and cause it to be automatically brought to rest after it has made one complete revolution. In the present construction, the operation of the clutch lever 360 is controlled by the position of the two carriages 30 and 32, the arrangement being such that as one or the other of the carriages reaches its rearward position, the clutch lever 360 is tripped, rendering the clutch 358 operative to cause rotation of the eccentric shaft 334. Immediately after being tripped, the clutch lever 360 returns to normal position and operates, as described in the aforesaid patent to disconnect the shaft 334 from its source of power at the completion of a single revolution. Further rotation of the eccentric shaft is thereupon arrested by means of a brake band 362 (Fig. 1) which encircles a hub on the driven clutch member and is contracted or expanded by a lever 364 that is pivoted at 366 to the frame 20 and to one extremity of which the opposite ends of the brake band are connected. The lever 364 is actuated by means of a link 368 which connects the opposite end of the lever with an extension of one of the pivot studs 330 that connect the rods 318 with the eccentric straps 332.

The means for tripping the clutch lever 360 comprises a trip-arm 372 (Figs. 2 and 8), which is carried at the forward end of an actuating lever 374 which is pivoted on a stud 376 projecting from the frame 20. The lever 374 carries at its rear extremity a cam roll 378, which is received in a cam path 380 (see also Fig. 3) on the outer side of the cam disk 202. The cam path 380 is designed to actuate the lever 374 at each

cycle of operations of the machine, so that the clutch 358 will be rendered operative to effect the reciprocation of the cutting-block upon the rearward movement of either of the die-carriages 30 and 32. Normally the trip-arm 372 is held in such a position that it will not engage the clutch lever 360 as the cam lever 374 is actuated by its cam. For this purpose the trip-arm 372 is provided with a tail 382 which is adapted to be held against a stop 384 on the cam lever by means of a spring 386 which connects the trip-arm and cam lever.

In order that the clutch lever 360 may be actuated by the trip-arm 372 when one or the other of the carriages 30 or 32 is in its rearward position, the following mechanism is provided. Pivotaly connected to the trip-arm 372 is the forward end of a link 388, (Fig. 8) the rear end of which is slotted, as indicated at 390, to receive a stud 392 projecting laterally from the upper end of an upright arm 394 (Figs. 3 and 8), the lower end of which is secured to a rock-shaft 396 which is journaled at its opposite ends in bearings in the frame 20. Also secured at its lower end to the rock-shaft 396 is a second upright arm 398, (Fig. 9 and at the right of Fig. 3) the upper extremity of which is adapted to be engaged by the lower end of a lever 400 which is pivoted on a stud 402 projecting inwardly from one side of the frame 20. The rock-shaft 396 is adapted to be rocked in a direction to shift the trip-arm 372 into operative relation with the clutch lever 360 by means of a suitably connected spring 404 (Fig. 9). The rock-shaft 396 is adapted to be rocked in the opposite direction to withdraw the trip-arm 372 from beneath the clutch lever 360 by means of the lever 400, the upper extremity of which is adapted to be engaged by one or the other of two rollers 406 and 408 (Figs. 2 and 3) which are mounted upon one side of the carriage 30. When the carriage 30 is in its forward position, the lever 400 is engaged by the roller 408 on the carriage, as shown in Fig. 2, and held thereby so that the lever 400 and the arms 398 and 394 on the rock-shaft 396 will be maintained in the position shown in said figure, against the tension of the spring 404. Upon the rearward movement of the carriage 30, the spring 404 is permitted to act through the arm 398 to rock the shaft 396 so as to swing the arm 394 in a direction to swing the trip-arm 372 beneath the end of the clutch lever 360. When the carriage 30 has reached its rearmost position, the roller 406 carried thereby engages the upper end of the lever 400 and insures that the trip-arm 372 will be positioned as above described. Upon the return of the carriage 30 to its forward position, the roller 408 thereon engages the upper end of the lever 400, causing said lever

400 to move in the opposite direction so as to swing the arms 398 and 394 rearwardly on the rock-shaft 396 against tension of the spring 404 to retract the trip-arm 372 to its normal inoperative position, as shown in Fig. 2.

In order that the movements of the other carriage 32 may cause the trip-arm 372 to be swung into and out of position to engage the clutch lever 360 in a manner similar to that above described, in which it is swung by the movements of the carriage 30, the following connections are provided between the carriage 32 and the trip-arm 372. Rising

from the rock-shaft 396, upon the opposite side of the link 388 from the arm 394, is an upright arm 412 (Figs. 3 and 8) which is similar to the arm 398, but which is loosely mounted upon the rock-shaft 396 and is adapted to be swung independently of the arm 398 to actuate the trip-arm. The arm 412 is adapted to be operatively connected with the trip-arm through the link 388 by means of a stud 414 which projects laterally

from the arm 412 and enters the slot 390 in said link. It will be observed that the studs 392 and 414 project into the slot 390 from opposite sides of the link 388 and that each stud extends less than half way through the link so that either is adapted to move in the slot without interfering with the other. The arm 412 is engaged at its upper end by the lower extremity of a lever 416, (Fig. 3) which is similar to the lever 400, and is pivoted upon a stud 418 projecting from the opposite side of the frame 20. The arm 412 is acted upon by a spring 420 which tends to hold the arm in engagement with the lever 416. The upper end of the lever 416 is adapted to be engaged by one or the other of two rollers which are carried at the side of the carriage 32, these rollers corresponding to the rollers 406, 408, which are carried by the other carriage 30, one of these rollers being indicated at 422 in Fig. 3.

The rollers on the carriage 32 cooperate with the lever 416 in the same manner as that in which the rollers on the carriage 30 cooperate with the lever 400. Upon the rearward movement of the carriage 32, the lever 416 is swung in a clockwise direction, (viewing Fig. 8) to permit the spring 420 to swing the arm 412 forwardly until the stud 414, carried by said arm reaches the forward end of the slot 390 in the link 388 and actuates said link to swing the trip-arm 372 beneath the end of the clutch lever 360. As the carriage 32 returns to its forward position, the other roller carried by said carriage swings the lever 416 in a counter-clockwise direction so that the arm 412 is swung rearwardly against the tension of the spring 420. This rearward movement of the arm 412 causes the stud 414 to engage the rear end of the slot 390 in the link 388 and then to actuate

the trip-arm 372 into operative relation with the clutch lever 360. The rollers on the carriage 32 cooperate with the lever 416 in the same manner as that in which the rollers on the carriage 30 cooperate with the lever 400. Upon the rearward movement of the carriage 32, the lever 416 is swung in a clockwise direction, (viewing Fig. 8) to permit the spring 420 to swing the arm 412 forwardly until the stud 414, carried by said arm reaches the forward end of the slot 390 in the link 388 and actuates said link to swing the trip-arm 372 beneath the end of the clutch lever 360. As the carriage 32 returns to its forward position, the other roller carried by said carriage swings the lever 416 in a counter-clockwise direction so that the arm 412 is swung rearwardly against the tension of the spring 420. This rearward movement of the arm 412 causes the stud 414 to engage the rear end of the slot 390 in the link 388 and then to actuate

said link to retract the trip-arm from beneath the clutch lever 360. It will be seen that the slot 390 in the link 388 is designed to permit the trip-arm 372 to be swung beneath the clutch lever 360 by the movement of either of the arms 398 or 412 while the other of said arms is maintained stationary in its normal position.

After each die and associated sole-supporting plate, upon which a sole has been placed by the operator, has been moved rearwardly by its respective carriage into position for the performance of the trimming operation, the cutting-block descends to trim the sole. As the cutting-block comes into contact with the sole, the sole-supporting plate on which the sole rests yields downwardly, relatively to the die, to permit the block to cooperate with the die. As the die and cutting-block cooperate, the sole is trimmed and inasmuch as the sole has previously been located relatively to the cutting edge of the die in the manner hereinbefore described, the trimming cut will be properly located with respect to the sewing-rib of the sole.

It is desirable that the dies shall engage a fresh portion of the cutting-block each time they cooperate therewith. To this end, provision is made for rotating the cutting-block a slight amount about a vertical axis after both dies have cooperated with the block. To effect such rotation of the cutting-block, the following mechanism is provided. Keyed to the cap plate 310 at the top of the stem 306 of the cutting-block holder 304, is a spur gear 428 (Fig. 1). The gear 428 is connected through an idler pinion 430 (Fig. 2) with a gear 432 which is splined upon the upper end of a vertical shaft 434, the upper and lower portions of which are journaled in the upper cross-head 34 and the frame 20, respectively. Secured to the lower end of the shaft 434 is a spiral gear 436 (Figs. 2 and 3), the teeth of which are cooperatively engaged by the teeth of a corresponding spiral gear 438, the latter being fast upon a short horizontal shaft 440 which is journaled in a bearing bracket 442 on the outside of the frame 20. Secured to the shaft 440 is a ratchet-wheel 444. The ratchet-wheel 444 and the shaft 440 are adapted to be rotated by means of a pawl 446 which is carried by a pawl-carrier 448 that is pivoted at 450 to a lug on the outside of the frame 20, the pawl being yieldingly pressed toward the ratchet teeth by means of a spring 452 which is interposed between the pawl and a portion of the pawl-carrier 448. The pawl-carrier 448 is connected by means of a link 454 (Figs. 3 and 9) with an arm 456 which is fast upon the outer end of a rock-shaft 458 that is adapted to turn in a bearing in the frame 20, the link having ball-and-socket joint connections with the

rocker member and with the arm 456. Secured to the opposite end of the rock-shaft 458, inside of the frame 20, is an arm 460, which is disposed substantially at right angles to the arm 456. The free end of the arm 460 is slotted to receive a slide-block 462, pivotally mounted upon the lower extremity of the lever 400 which is rocked periodically by the rollers 406 and 408 upon the carriage 30. With this construction, when the carriage 30 is moved rearwardly and the lever 400 is swung in a clockwise direction, viewing Fig. 2, the pawl carrier 448 will be rocked in a direction to move the pawl through the space of one tooth across the periphery of the ratchet-wheel 444. Upon the return of the carriage 30 to its forward position, and the resulting swinging of the lever 400 in a counter-clockwise direction, the pawl-carrier 448 will be rocked in the opposite direction causing the ratchet-wheel 444 to be stepped ahead through the space of one tooth. By means of the connections between the shaft 440 and the stem 306 of the cutting-block carrier, the cutting-block will be rotated so that a fresh portion of its surface will be presented to the dies the next time it cooperates therewith.

Immediately upon the start of the forward movement of the carriage, the disengagement of the lug 298 from the toe 297 of the dog 293 permits the spring 296 to return the dog to its normal position, as shown in Fig. 5. After the dog 293 has reached normal position, the pin-and-slot connection 295 between the link 292 and the arm 291 permits the link to move, relatively to said arm, until the pin is positioned at the rear extremity of the slot, thus leaving the spring 233 free to withdraw the locking bolt 218 when the arm 248 is again released from the latch 242.

During the return or forward movement of each die-carriage, the coupling member carried thereby is relatched in its raised or inoperative position, in order that the carriage may remain stationary in its forward position, until the trimmed sole has been removed from the sole-supporting plate and a new sole placed thereon and the trip-rod has again been depressed by the operator. The means associated with each die-carriage for disconnecting its coupling member from its respective actuator slide and relatching it in disengaged position, comprises a dog 468 (Fig. 5), which is connected to an arm 470 depending from the coupling member, and a stationary cam 472 (see also Fig. 2) on the frame with which said dog is adapted to cooperate. As shown in Fig. 5, the lower end of the depending arm 470 on the coupling member is bifurcated to receive the dog 468 which is pivotally mounted upon a pin 474 carried between the bifurcated ends of the arm 470. The dog 468 carries a pin 476, the ends of

which project beyond the opposite sides of the dog and are received in segmental slots 478 in the forks of the arm 470. A leaf spring 480, which is secured to the coupling member 216, engages the dog 468 and normally holds the dog in the position shown in Fig. 5, with the projecting ends of the pin 476 engaging the lower ends of the slots 478 in the arm 470. This construction permits the dog to yield forwardly at the start of the rearward movement of the carriage, so that the dog may ride freely over the face of the fixed cam 472. Upon the forward or return movement of the carriage, however, when the dog 468 engages the rear edge of the cam 472, the dog will not yield relatively to the arm and consequently the dog and the coupling member are swung upwardly as a unit about the pivot stud 266 until the arm 272 on the coupling member is engaged by the hooked end of the latch 274. The coupling members are thus disengaged from their respective actuator slides and the carriages will remain stationary in their forward positions until the operator again depresses one of the trip-
rods 220.

After the cutting-block has cooperated with one of the dies to trim the sole, the friction between the trimmed edge of the sole and the inner face of the die may be sufficient to prevent the sole-supporting plate from being returned by the spring 62 to its normal elevated position, and thus stripping the trimmed sole from the die. In order to provide positive means which will insure the stripping of the trimmed soles from the dies, a stationary cam 484 (Figs. 2 and 5) is secured to the overhanging frame portion 22 and arranged to engage a pair of cam rolls 486, one of which is provided on each of the cross-bars 56 which connect the lower ends of the posts 48 upon which the sole-supporting plates are mounted. Immediately before either carriage reaches its forward position, if the sole-supporting plate has not already been returned to its normal raised position by the spring 62, the cam roll 486 carried thereby rides up the inclined face of the respective cam 484, thus positively raising the sole-supporting plate and stripping the trimmed sole from the die.

When the carriage finally comes to rest in its forward position, a cam-shaped edge 488 (Fig. 5) at the hooked end of the latch 226 rides over the beveled upper end of the locking bolt 218 until the hooked portion of the latch drops behind the shoulder 224 on the locking bolt, thus locking the carriage against rearward movement.

The present machine will operate effectively and rapidly to perform the sole trimming operation. The particular construction of the sole-locating devices on the sole-

supports and the relative arrangement of these devices and the associated dies is such that the location of the trimming cut will be gaaged from the sewing-rib of the sole. As a result, the feather or marginal portion of the sole outside of the sewing-rib will be of uniform dimensions on all soles trimmed by the same die. The sole-supporting and locating devices being retracted from beneath the cutting-block when the soles are placed thereon, the operator is enabled to watch the sole locating operation carefully so as to be sure that the sole is properly positioned before depressing the trip-rod to cause the sole to be advanced toward the cutting-block. It will be apparent that the rapidity of operation of the machine is greatly increased by the employment of a pair of sole-supports and a pair of trimming dies, since with this construction one sole may be located relatively to one of the dies while another sole is being trimmed by the cooperation of the other die with the cutting-block.

While it is preferred to employ the specific construction and arrangement of parts herein shown and described, it will be understood that this construction and arrangement is not essential except so far as specified in the claims, and may be modified without departing from the broader features of the invention.

What is claimed as new is:—

1. A machine for operating upon welt insoles provided with ribs or shoulders at substantial distances from the margins of the insoles having, in combination, means comprising a die for trimming the margin of an insole, and means constructed and arranged to engage the ribbed face of the insole inside of the rib or shoulder thereon to support it in position to be trimmed.

2. A machine for operating upon shoe soles having, in combination, means comprising a die for trimming the margin of a sole, means for supporting the sole for the trimming operation, and means for locating the sole relatively to the trimming means.

3. A machine for operating upon shoe soles provided with ribs or shoulders at substantial distances from the margins of the insoles having, in combination, means adapted to engage an insole inside of the rib or shoulder on one face thereof, for supporting the insole in position to be trimmed, a die surrounding the support, and means for causing the die to trim the margin of the insole.

4. A machine for operating upon welt insoles provided with ribs or shoulders at substantial distances from the margins of the insoles having, in combination, means comprising a die for trimming the margin of an insole, and means for relatively locating the trimming means and the insole so

that the edge of the trimmed margin will bear a predetermined relation to the sewing-rib of the insole.

5. A machine for operating upon shoe soles having, in combination, a die, a cutting-block for cooperating with the die to trim the margin of a sole, and means for positioning the sole laterally with respect to the cutting edge of the die and for supporting the sole between the die and the cutting-block preparatory to the performance of the trimming operation.
6. In a machine for operating upon shoe soles, the combination with a die and a co-operating cutting-block for trimming the margin of a sole, of means for locating the margin of the untrimmed sole in a lateral direction relatively to the cutting edge of the die.

- 20 7. In a machine for operating upon shoe soles, the combination with a die and a co-operating cutting-block for trimming the margin of a sole, of a work support constructed and arranged to locate the sole in a lateral direction relatively to the die for the trimming operation and to strip the sole from the die after it has been trimmed.

8. In a machine for operating upon shoe soles, the combination with a die and a co-operating cutting-block for trimming the margin of a sole, of a yieldable work support normally positioned to support a sole above the cutting edge of the die and adapted to be displaced by the sole as the die and cutting-block cooperate, and means for positively restoring the work support to its normal supporting position after the sole has been trimmed to strip the sole upon the die.

- 40 9. In a machine for operating upon welt insoles, the combination with a die and a co-operating cutting-block for trimming the margin of an insole, of means for engaging the sewing rib of the insole to locate the sole margin relatively to the cutting edge of the die for the trimming operation.

10. In a machine for operating upon welt insoles, the combination with a die and a co-operating cutting-block for trimming the margin of an insole, of means for engaging the inside of the sewing rib about the toe of the insole to locate the insole relatively to the die for the trimming operation.

- 55 11. In a machine for operating upon welt insoles, the combination with a die and a co-operating cutting-block for trimming the margin of an insole, of a work support adapted to engage the ribbed face of the insole to support the insole above the cutting edge of the die and to engage the sewing-rib to locate the insole in its own plane in position to be trimmed.

- 60 12. In a machine for operating upon welt insoles, the combination with a die and a

cooperating cutting-block for trimming the margin of an insole, of a positioning plate having its edge shaped to conform to and engage the inside of the sewing-rib of the insole, to locate the margin of the insole relatively to the die for the trimming operation.

13. In a machine for operating upon welt insoles, the combination with a die and a co-operating cutting-block for trimming the margin of an insole, of a positioning device constructed and arranged to engage the sewing-rib at the toe of the insole to locate the forepart of the insole relatively to the die, and means on the positioning device for locating the heel end of the insole relatively to the die.

14. A machine for trimming shoe soles having, in combination, a cutting-block, a pair of dies adapted to alternately cooperate with the cutting-block to trim a sole, and means mounted inside of each die for supporting a sole and for positioning it in a lateral direction relatively to the die for the trimming operation.

90 15. A machine for operating upon shoe soles having, in combination, a die, a co-operating cutting-block for trimming the margin of a sole, a normally retracted carriage upon which the die is mounted adapted to be advanced to move the die into position for cooperation with the cutting-block, means for actuating the carriage, means under the control of the operator for rendering the actuating means effective, and means for automatically rendering the actuating means ineffective after each reciprocation of the carriage.

100 16. A machine for operating upon shoe soles having, in combination, a die, a reciprocating cutting-block for cooperating with the die to trim the margin of a sole, means for actuating the cutting-block, a die-carriage adapted to be reciprocated to advance the die into the field of operations of the cutting-block and to withdraw the die therefrom, and means for actuating the die-carriage.

110 17. A machine for operating upon shoe soles having, in combination, a die, a cutting-block for cooperating with the die to trim the margin of a sole, a normally retracted carriage upon which the die is mounted adapted to be moved into position for cooperation with the cutting-block, and means under the control of the operator for actuating the carriage.

120 18. A machine for operating upon shoe soles having, in combination, a die, a cutting-block for cooperating with the die to trim the margin of a sole, a normally retracted carriage upon which the die is mounted adapted to be advanced into position for cooperation with the cutting-block, continuously operating, normally ineffective actu-

ating means for the carriage, and means for rendering said actuating means effective to actuate the carriage.

19. A machine for operating upon shoe soles, having in combination, a die, a cutting-block for cooperating with the die to trim the margin of a sole, a normally retracted carriage upon which the die is mounted adapted to be advanced into position for cooperation with the cutting-block, continuously operating, normally disconnected actuating means for the carriage, means for connecting said actuating means to actuate the carriage, and means for disconnecting said actuating means from the carriage after a single reciprocation of the latter.

20. A machine for operating upon shoe soles having, in combination, a die, a cutting-block for cooperating with the die to trim the margin of a sole, a normally retracted carriage upon which the die is mounted adapted to be advanced to cooperate with the cutting-block, means for advancing and retracting the carriage, and means for locking the carriage in retracted position.

21. A machine for operating upon shoe soles having, in combination, a die, a cutting-block for cooperating with the die to trim the margin of a sole, a normally retracted carriage upon which the die is mounted adapted to be advanced to cooperate with the cutting-block, means for advancing and retracting the carriage, means for automatically locking the carriage in retracted position, and means under the control of the operator for releasing the locking means.

22. A machine for operating upon shoe soles having, in combination, a die, a cutting-block for cooperating with the die to trim the margin of a sole, a normally retracted carriage upon which the die is mounted adapted to be advanced to cooperate with the cutting-block, continuously operating normally disconnected actuating means for the carriage, means for locking the carriage in retracted position, and means for releasing the locking means and rendering said actuating means effective to advance the carriage.

23. A machine for operating upon shoe soles having, in combination, a die, a cutting-block for cooperating with the die to trim the margin of a sole, a normally retracted carriage upon which the die is mounted adapted to be advanced into position for cooperation with the cutting-block, means for actuating the carriage, a latch normally effective to hold the carriage in retracted position, means for releasing the latch, and means for automatically restoring the latch to operative position.

24. A machine for operating upon shoe soles having, in combination, a die, a reciprocating cutting-block for cooperating with the die to trim the margin of a sole, means for actuating the cutting-block, a normally

retracted carriage upon which the die is mounted adapted to be advanced in the field of operations of the cutting-block, means for actuating the carriage, a continuously reciprocating normally disconnected actuator for the carriage, and means rendered active at the will of the operator for connecting the actuator with the carriage.

25. A machine for operating upon shoe soles having, in combination, a die, a cutting-block for cooperating with the die to trim the margin of the sole, normally inoperative means for operating the cutting-block, a carriage upon which the die is mounted adapted to be moved into position for cooperation with the cutting-block, means for operating the carriage, and means controlled by the position of the carriage for rendering operative the means for operating the cutting-block.

26. A machine for operating upon shoe soles having, in combination, a die, a cutting-block for cooperating with the die to trim the margin of the sole, a normally retracted carriage upon which the die is mounted adapted to be advanced into position to cooperate with the cutting-block, a continuously operating actuator for the carriage, a coupling member on the carriage adapted to be positioned for operative engagement with the actuator, and means for bringing the coupling member into position to be engaged by the actuator.

27. A machine for operating upon shoe soles having, in combination, a die, a cutting-block for cooperating with the die to trim the margin of the sole, a normally retracted carriage upon which the die is mounted adapted to be advanced into position to cooperate with the cutting-block, a continuously operating actuator for the carriage, a coupling member on the carriage adapted to be positioned for operative engagement with the actuator, means for bringing the coupling member into operative engagement with the actuator, and means for disengaging the coupling member and the actuator.

28. A machine for operating upon shoe soles having, in combination, a cutting-block, a pair of normally retracted dies adapted to be advanced into position for cooperation with the cutting-block, a pair of continuously reciprocating normally disengaged actuators operating alternately to advance the dies, and means for connecting either die with its actuator at the will of the operator.

29. A machine for operating upon shoe soles having, in combination, a cutting-block, a hollow die adapted to cooperate with the cutting-block to trim the margin of a sole, a work-supporting and locating member normally positioned with its supporting face above the cutting edge of the die to support a sole with its margin overlapping said cut-

ting edge, said member adapted to be forced inside the die during the trimming operation, a carriage upon which the die and work supporting member are mounted, the carriage being normally positioned at one side of the cutting-block and adapted to be moved into position for cooperation with the latter, and means operable to restore said member to normal position upon the retraction of the carriage.

30. In a machine for trimming soles, a sole positioning device, a sole die, a support for the die adapted to carry dies of various sizes, and means carried by the die support and cooperating with any given die for locating the die in a predetermined position relatively to the sole positioning device.

31. In a machine for trimming soles, a die support, a die having a sole-shaped wall, and means for locating the die in a definite lateral position on the support comprising a tongue and groove connection between said parts extending longitudinally of the die and transversely of the wall at the toe and heel of the die.

32. In a machine for trimming soles, a sole-support, a hollow die having a sole-shaped wall surrounding said support, said wall being provided with a transverse groove at its base adjacent heel and toe ends of the die, a support for the die, and means on the die support for entering said grooves to locate the die transversely relatively to the sole-support.

33. In a machine for trimming soles, a sole die, a die-holder, means mounted upon the die-holder for locating the sole relatively to the die, and means for locating the die upon the die-holder in a predetermined position relatively to the sole locating means.

34. In a machine for trimming soles, the combination with a sole die and a cooperating cutting-block, of a die-holder, a work support mounted upon the die-holder for supporting a sole between the die and the cutting-block and for locating the sole relatively to the die, and means for locating the die upon the die-holder in a predetermined position relatively to the work support.

35. In a machine for trimming soles, the combination with a sole die and a cooperating cutting-block, of a die-holder, a work support mounted upon the die-holder for supporting a sole between the die and the cutting-block and for locating the sole relatively to the die, means for locating the die upon the die-holder in a predetermined position relatively to the work support, and means for removably securing the die to the die-holder.

36. In a machine for trimming soles, the combination with a sole die and a cooperat-

ing cutting-block, of a die-holder, a work support mounted upon the die-holder for supporting a sole between the die and the cutting-block and for locating the sole relatively to the die, means for locating the die upon the die-holder in a predetermined position relatively to the work support, and means adjustable to dies of different sizes for securing the die in its desired position upon the holder.

37. In a machine for trimming soles, a sole-support, a hollow die having a sole-shaped wall surrounding said support, a die support, and means for gripping said wall at one end of the die to locate it longitudinally relatively to the sole-support.

38. In a machine for trimming soles, a sole-support, a hollow die having a sole-shaped wall surrounding said support, a die support, and adjustable means for engaging said wall at one end of the die to locate dies of different sizes longitudinally relatively to the sole-support.

39. In a machine for trimming soles, a sole-support, a die support, a hollow sole-shaped die mounted on the die support having a cutting edge surrounding the sole-support and a lower edge for engaging the die support, means on the die support and die for locating the latter transversely relatively to the sole-support, and positioning members upon the die support for engaging both the inner and outer faces of the die at one end thereof to locate the die longitudinally relatively to the sole-support.

40. In a machine for trimming soles, the combination with a sole die provided with holes in the walls thereof, of a die-holder, means for locating the die in a predetermined position on the die-holder, and means constructed and arranged to enter the holes in the die for securing the die in adjusted position.

41. In a machine for trimming soles, the combination with a sole die and having holes in the opposite side walls thereof, of a die-holder, means for locating the die in a predetermined position on the holder, and a plurality of clamping members mounted on the holder constructed and arranged to enter the holes in the die to seat the die after it has been located upon the holder.

42. In a machine for trimming soles, the combination with a sole die provided with holes in the side walls thereof, of a die-holder, means for locating the die in a predetermined position on the holder, a device for securing the die to the holder in adjusted position comprising a plurality of arms having portions for entering the holes in the die, the device being adjustable to accommodate dies of different sizes, and means for actuating the arms in a direction to clamp the die to the holder.

43. In a machine for trimming soles, the

combination with a sole die provided with holes in the side walls thereof, of means for locating the die in a predetermined position on the holder, a clamping device on the holder comprising a plurality of arms having projections thereon for entering the holes in the die, the arms being adjustable to accommodate dies of different sizes, means for adjusting the clamping arms to cause said projections to enter the holes in the die, and means for actuating the clamping arms in a direction to clamp the die to the holder.

44. In a machine for trimming soles, a sole-shaped die having an upwardly directed cutting edge, the die having holes in the walls thereof, a support for the die, a pair of arms on the die support adapted to project into the interior of the die adjacent said holes and adapted to be adjusted laterally toward and from the walls of the die, a clamping stud projecting laterally from each arm and adapted to enter the adjacent holes in the die, means for adjusting the arms laterally to project the clamping studs into said holes or to withdraw the studs therefrom, and means for moving the arms longitudinally to cause the die to be securely clamped against the support.

45. In a machine for trimming soles, a sole-shaped die having an upwardly directed cutting edge and a plurality of clamping holes severally located in the opposite side walls of the die adjacent both the toe and heel ends thereof, a support for the die, a pair of clamping arms on the support adapted to project into the interior of the die adjacent the clamping holes at the heel end thereof, a second pair of clamping arms on the support adapted to project into the interior of the die adjacent the clamping holes at the toe end of the die, a clamping stud projecting laterally from each clamping arm and adapted to enter the adjacent clamping hole in the die, means for adjusting the clamping arms laterally to cause the clamping studs to enter or to be withdrawn from clamping holes in directions substantially perpendicular to the walls of the die, and means for moving the arms longitudinally to cause the die to be securely clamped against the die support.

46. In a machine for trimming welt insoles having a jig-hole in the heel end thereof, a sole-shaped die, a sole-support constructed and arranged to locate the sole in a definite position in its own plane relatively to the die, and means on the sole-support for entering the jig-hole in the sole to maintain the position of the sole when it has been properly located relatively to the die.

47. In a machine for trimming welt insoles having a jig-hole in the heel end thereof, a sole-support, a sole-shaped die surrounding the support, a forepart plate on

the support to engage the inner side of the sewing-rib and position the sole laterally with relation to the die, and a jig pin on the support for entering the jig-hole to maintain the position of the sole when it has been located by the forepart plate.

48. In a machine for trimming soles having a jig-hole at the heel end thereof, a sole-support, a jig pin in the sole-support for entering the jig-hole in the sole, a sole-shaped die surrounding the sole-support, a support for the die, and means on the die support for locating the die longitudinally with respect to the pin in the sole-support.

49. In a machine for operating upon welt insoles, the combination with a sole-shaped die and a cooperating cutting-block for trimming the margin of the sole, of a support for the sole constructed and arranged to locate it in a definite position in its own plane relatively to the die when the sole has been placed upon the support in a predetermined manner, and means for indicating when the sole has been properly placed on the support.

50. In a machine for operating upon welt insoles, the combination with a sole-shaped die and a cooperating cutting-block for trimming the margin of a sole, of a sole supporting plate having its edge shaped to fit the contour of the inside of the sewing-rib of the sole to locate the sole relatively to the die, and means on the supporting plate to indicate when the sole has been properly placed thereon.

51. In a machine for trimming welt insoles, a sole-shaped die, a sole-support within the die arranged to support the sole with its margin extending beyond the cutting edge of the die, and means on the support for engaging the sole to position the sole for a trimming cut along a predetermined line relatively to the sewing-rib.

52. In a machine for trimming welt insoles, a sole-support constructed to engage the sole and locate it in a definite position thereon with respect to its sewing-rib, a sole-shaped die, and means to locate the die in a definite position outside of the sole-support for trimming the margin of the sole at a predetermined distance from the sewing-rib.

53. In a machine for trimming welt insoles, a sole-support provided with means for engaging the sewing-rib to locate the sole on said support, a sole-shaped die surrounding the support, means to locate the die in a predetermined position relatively to the sewing-rib and additional means on the sole-support for engaging the sole to prevent displacement relatively to the die.

54. In a machine for trimming welt insoles, a sole-support, a sole-shaped die surrounding the support, and means on the support cooperating with the sole to locate the sole with its sewing-rib in a definite posi-

tion both laterally and longitudinally with respect to the die.

55. A machine for trimming shoe soles having, in combination, a cutting-block, a pair of dies arranged to come to rest at the front of the machine and to move alternately into co-operative relation with respect to the cutting-block, and means associated with each die for supporting a sole in position relatively to the die for a trimming operation.

56. In a machine for operating upon welt insoles provided with ribs or shoulders at substantial distances from the margins of

15 the insoles, means for trimming the margin of an insole, and means constructed and arranged to engage solely within the ribbed face of the insole to support it in position to be trimmed.

20 57. In a machine for operating upon welt insoles provided with ribs or shoulders at substantial distances from the margins of the insoles, means for trimming the margin of an insole, and a support of a size and

25 shape to engage one face of the insole entirely within the rib or shoulder thereon for supporting and locating the insole during a trimming operation.

30 58. In a machine for operating on welt insoles provided with ribs or shoulders at substantial distances from the margins of the insoles, means comprising a die for trimming the margin of an insole, and a plate located within the die in spaced relation with respect to the walls of the die, the said plate serving to engage an insole entirely within the rib or shoulder thereon to support and position the insole with respect to the die whereby the margin of the insole is properly trimmed upon operation of the trimming means.

35 59. A machine for operating upon shoe soles having, in combination, a die, a cutting-block for co-operating with the die to trim the margin of the sole, means for operating the cutting-block, a carriage upon which the die is mounted adapted to be moved into position for co-operation with the cutting-die, means for operating the carriage, and means rendered operative by the carriage as it arrives in co-operative relation with respect to the cutting-block for initiating operation of the cutting-block operating means.

40 60. In a machine for operating upon shoe soles, a cutter member and a cutting-block member arranged to co-operate in trimming the margin of a sole, means for operating one of the members to effect a trimming operation, a carriage upon which one of the members is mounted for movement into co-operative relation with the other member, means for operating the carriage, and means controlled by the carriage for initiating a 45 co-operative movement of the cutter mem-

ber and the cutting-block member to effect a trimming operation upon a sole.

61. In a machine of the character described, a die, a cutting-block mounted for reciprocation toward and from the die located in co-operative relation thereto, a carriage for the die movable to carry the die into and out of co-operative relation with respect to the cutting-block, and power means controlled by the carriage for reciprocating the cutting-block to effect in conjunction with the die cutting operations upon material interposed between the die and block.

62. In a machine of the character described, a plurality of dies each having a carriage movable to position the die alternately in work-receiving and work-cutting positions, a cutting-block for co-operation with the dies, and power means controlled by each of the carriages for causing reciprocation of the cutting block when a die has been properly located in co-operative relation thereto.

63. In a machine of the character described, a plurality of dies each having a carriage movable to position the die in work-receiving and work-cutting positions, a cutting-block for co-operating with the dies, means under the control of the operator for moving the carriages one at a time to position a die in co-operative relation to the cutting-block, and power means controlled by each of the carriages for causing relative movement between a die and a cutting-block to effect cutting operations on the material interposed between the die and block.

64. In a machine for trimming soles each having a jig-hole in the heel end thereof, a sole-shaped die, and means located in the die for engaging the jig-hole to position the sole properly with respect to the die.

65. In a machine for trimming soles each having a jig-hole therein, a sole-shaped die, and a pin located within the die for engaging the jig-hole to position the sole with respect to the die preliminarily to the sole cutting operation.

66. In a machine for trimming pieces of material for shoe part blanks comprising, a die of the shape of the desired blank, and means within the periphery of the die for engaging a positioning surface on the piece of material to locate the latter relatively to the die preliminarily to a trimming operation.

67. In a machine for cutting a shoe part blank from a piece of material provided with a positioning surface, cutting means, and means located within the cutting means for engaging with the positioning surface of the piece of material to locate the latter with respect to the cutting means.

68. In a machine for cutting a shoe part from a piece of material having a jig-hole

therein, a die having a cutting edge of the shape of the desired shoe part, and a jig pin located inside of the cutting edge of the die for engagement with the jig-hole to locate the piece of material preliminarily to the cutting operation.

69. In a machine for cutting soles from pieces of material each having a jig-hole therein, a die having a cutting edge of the shape of the desired sole, a jig pin adapted to engage with the jig-hole in the piece of material and to project across the plane of the cutting edge of the die within the periphery thereof to locate the piece of material prior to the cutting operation, and means for yieldingly mounting the pin so that it may retreat away from the plane of the cutting edge of the die during the cutting operation.
70. In a machine for cutting shoe part blanks from pieces of material each having a jig-hole therein, a die of the shape of the desired shoe part blank, a support for the piece of material located within the die, and a jig pin mounted in the support and adapted to engage with the jig-hole in the piece of

material to locate the latter for a cutting operation.

71. In a machine for cutting shoe part blanks from pieces of material each provided with a positioning surface, a die of the shape of the desired blank, a support located within the die on which the piece of material rests preliminarily to the cutting operation, and means on the support for engaging said positioning surface so as to locate and hold the piece of material in proper position.

72. In a machine of the class described, an upwardly facing die, and a work supporting means located inside of the die and constructed and arranged to position the work laterally of the die, said means being depressible to permit the work to be pressed upon the cutting edge of the die.

73. In a machine of the class described, an upwardly facing die, a presser member, a work support located within the periphery of the die, and a jig pin within the die and depressible to permit the work to be pressed into the die by the presser member.

FREDERICK H. PERRY.
